UNITED STATES PATENT OFFICE.

RAYMOND THEODORE REED, OF WICHITA, KANSAS.

COLLAPSIBLE TENT.

1,415,482.

Specification of Letters Patent.

Patented May 9, 1922.

Application filed August 6, 1921. Serial No. 490,278.

To all whom it may concern:

Be it known that I, RAYMOND T. REED, a citizen of the United States, and a resident of Wichita, in the county of Sedgwick and State of Kansas, have invented certain new and useful Improvements in Collapsible Tents, of which the following is a specification.

My invention is an improvement in collapsible tents, and the invention has for its object to provide a device of the character specified capable for use in any connection, but especially adapted for children's play tents, wherein a folding frame is provided having a flexible cover and so arranged that the supporting elements of the frame may be folded down flat upon each other, together with the flexible cover, for purposes of storage or the like.

20 In the drawings:

Figure 1 is a perspective view of the improved tent in unfolded position;

Figure 2 is a similar view showing the manner of folding the tent;

25 Figure 3 is a perspective view of the frame unfolded;

Figure 4 is a similar view of the tent folded, with the position of the frame members indicated in dotted lines;

30 Figure 5 is a perspective view of the connection between the ends of the frame members.

In the present embodiment of the invention a suitable frame is provided, consisting 35 of uprights 1, in the present instance six in number. These uprights are connected at their tops by a ring 2, the said ring being passed through transverse openings 2^a near the tops of the uprights, and the uprights are 40 thus mounted to swing upon the ring or to slide upon the ring toward and from each other.

The uprights are connected at their lower ends by folding arms, each arm consisting 45 of similar sections 3 and 4 pivoted at their outer ends to the uprights and at their adjacent ends connected by a rule joint, which permits them to swing freely upward at the joint, but limits their downward swinging 50 movement to a position where they are in alinement. Between two of the uprights the folding arms 3-4 are omitted and at this point is the entrance of the tent. A hook 5 of suitable length is pivoted to one of 55 the uprights at one side of the entrance to the tent, and is adapted to engage an eye 6 on the upright at the opposite side of the en-

trance to prevent movement of the uprights, forming the entrance, away from each other.

The tent is covered by a covering 7 of 60 flexible material, as, for instance, canvas, the said covering being secured to the uprights in any suitable manner, and the edges of the cover lap at one of the uprights forming the entrance to the tent. The outermost 65 edge of the covering is detachably connected with this upright by snap buttons 8 or the like, and thus a movable fly 9 is provided, forming a door for the tent. This door may be snapped down into place to cover the entrance opening or it may be swung open as shown in Figures 1 and 2.

In order to fold the tent, the hook 5 is detached and the arms 3 and 4 are swung upwardly at their joints, as indicated in 75 Figure 2, and the uprights are slipped about on the ring 2 until they fold smoothly upon each other. The flexible covering will fold in double folds as shown in Figure 4, and the entire frame and covering folds thus into 80 small compass for transportation, packing or the like.

To cover the upper ends of the uprights, where they are exposed by the ring, and which point is not covered by the covering 85 7, a cap 10 is provided, the said cap being secured to the covering 7.

I claim:

1. A folding tent comprising a series of uprights, a ring upon which the upper ends 90 of the uprights are mounted to swing and slide into spaced relation or into contact with each other, folding arms connecting the lower ends of the adjacent uprights and a covering for the uprights, said folding arms 95 consisting of sections pivoted to the uprights at their outer ends and connected by a rule joint at their adjacent ends, one of the arms being omitted, and a hook pivoted to one upright at the omitted arm and an eye on the 100 other upright for engagement by the hook.

2. A folding tent comprising a series of uprights, a ring upon which the upper ends 105 of the uprights are mounted to swing and slide into spaced relation or into contact with each other, folding arms connecting the lower ends of the uprights adjacent each other, and a covering for the uprights, said folding arms consisting of sections pivoted to the uprights at their outer ends and connected by a rule joint at their adjacent 110 ends.

RAYMOND THEODORE REED.
